UNITED STATES PATENT OFFICE

96,203

DESIGN FOR A HOBBYHORSE

Norbert J. Schaal, Riverton Heights, Washington

Application April 13, 1935, Serial No. 56,352

Term of patent 3½ years

To all whom it may concern:

Be it known that I, Norbert J. Schaal, a citizen of the United States, residing at Riverton Heights, in the county of King and State of Washington, have invented a new, original, and ornamental Design for a Hobby Horse, of which the following is a specification, reference being had to the accompanying drawing, forming part thereof.

The figure is a perspective view of a hobby horse, showing my new design.

I claim:

The ornamental design for a hobby horse, as shown.

NORBERT J. SCHAAAL.
